UNITED STATES PATENT OFFICE

105,642

DESIGN FOR A MACHINE TOOL POWER UNIT

Harold Van Doren, Toledo, Ohio, assignor to
Ex-Cell-O Corporation, a corporation of Michigan

Application April 14, 1937, Serial No. 68,751

Term of patent 14 years

To all whom it may concern:

Be it known that I, Harold Van Doren, a citizen of the United States, residing at 1217 Madison Avenue, Toledo, in the county of Lucas and State of Ohio, have invented a new, original, and ornamental Design for a Machine Tool Power Unit, of which the following is a specification, reference being had to the accompanying drawing, forming part thereof.

Figures 1 and 2 are perspective views taken from opposite sides of the machine tool power unit showing the new design.

The dominant feature of the design resides in the ribs or raised strip-like parts extending along each side of the machine tool power unit and then upwardly at one end and partly over the top of the drill unit.

I claim:

The ornamental design for a machine tool power unit substantially as shown and described.

HAROLD VAN DOREN.
